Primary Examiner — Richard Edgar*Assistant Examiner* — Cheng Chen(74) *Attorney, Agent, or Firm* — Fresh IP PLC; Clifford D. Hyra; Micah Gunn(57) **CLAIM**

The ornamental design for a compressor as shown and described.

DESCRIPTION

FIG. 1 is a front view of a compressor, showing my design;

FIG. 2 is a front perspective view thereof;

FIG. 3 is a right side view thereof;

FIG. 4 is a rear view thereof;

FIG. 5 is a left side view thereof; and,

FIG. 6 is a top view thereof.

The broken lines illustrate portions of the compressor that form no part of the claimed design.

1 Claim, 6 Drawing Sheets(56)
